JOHN JEWELL, OF DULUTH, MINNESOTA.

HAND-TRUCK.

1,367,396.

Specification of Letters Patent.

Patented Feb. 1, 1921.

Application filed May 21, 1920. Serial No. 383,268.

To all whom it may concern:

Be it known that I, JOHN JEWELL, a citizen of the United States, residing at Duluth, in the county of St. Louis and State 5 of Minnesota, have invented certain new and useful Improvements in Hand-Trucks, of which the following is a specification, reference being had therein to the accompanying drawing.

10 This invention relates to hand trucks such as are commonly used in the handling of freight about warehouses and the like and has special reference to a truck of this character having power storing and operating means.

15 The object is to provide simple mechanical means whereby when the truck is operated down grade in either direction with a considerable load thereon, energy will be 20 mechanically stored therein, for subsequent use in propelling the truck, and, at the same time, acting as a break to the truck when descending such grade. Another object is 25 to provide means whereby the power thus stored may be subsequently utilized at any desired time for operating the truck in either direction. Other objects and advantages of the specific structure hereinafter described will appear therein.

30 In the accompanying drawing forming part of this application, and in which like reference characters indicate like parts:

Figure 1 is a bottom plan view of one of my improved trucks;

35 Fig. 2 is a central vertical section taken on the line 2—2, Fig. 1:

Fig. 3 is a transverse sectional view taken on the line 3—3, Fig. 1;

40 Fig. 4 is a similar sectional view taken on the line 4—4, Fig. 2, looking toward the wheels of the truck;

Fig. 5 is a fragmental sectional view of one of the handles of the truck taken on the line 5—5, Fig. 1; and

45 Fig. 6 is a horizontal sectional view taken on the line 6—6, Fig. 2, looking downwardly.

The chassis of the truck comprises the side members 1 and suitable cross-beams or 50 members 2, 3, 4, 5 and 6, which are common to such structures and the side members 1 terminate in suitable handles 7 and 8 by

which the truck is manually operated. To the under edges of the side members 1, and adjacent to the end opposite to that of the handles 7 and 8, is journaled the transverse shaft 9, which fixedly carries the wheels 10 of the truck, all of which are known to be common in the art.

55 My invention comprises the following 60 mechanism:

Upon the shaft 9 are mounted two spaced beveled gears 11 and 12, they being fixed to a sleeve 13 surrounding the shaft and splined thereupon as shown at 14, so that 65 they are readily susceptible of reciprocal adjustment upon the shaft 9. The sleeve 13 extends some little distance beyond the gear 12 as at 15 and has formed thereupon a projecting disk or wheel 16 which is engaged 70 upon either side thereof by rollers 17 pivotally carried as at 18 upon the wider end 19 of the lever 20 which is pivoted at 21 to the under side of the cross-beam 4, the operating end of the lever extending horizontally of the adjacent side member 1 of the chassis to a point beyond the extreme end cross-beam 6, as at 22, where it is accessible 75 to the operator of the truck and at which point it is held in any one of three predetermined positions by the notched plate 23 attached to and depending from the cross-beam 6. Thus, when the end 22 of the lever 20 is thrown to the outermost notch in the plate 23, the beveled gear 12 on the shaft 85 9 will be thrown into engagement and mesh with the gear 24 on the shaft 25 which latter will be described later, and, when the end 22 of the lever 20 is thrown into engagement with the extreme innermost notch 90 of the plate 23, the beveled gear 11 will be engaged with the gear 24 simultaneously with the gear 12 being disengaged therefrom and when the end 22 of the lever 20 is in the centermost notch of the plate 23 95 neither one of the gears 11 or 12 will be engaged with the gear 24, and the shaft upon which the former are mounted, which is the axle 9 of the truck, will be free to rotate in either direction resulting in the truck acting in every respect as a common hand truck.

100 The gear 24 is fixedly attached to the shaft 25, the latter being journaled on the

under side of the cross-pieces 3 and 4. Surrounding the end of the shaft 25 toward the handles 7 and 8 is a telescopic sleeve 26 carrying upon its inner end a beveled gear 27 and also on its outer end a ratchet wheel 28, both being formed integral with the sleeve, and that portion of the shaft 25 surrounded by the sleeve has an axle hole 29 therein into which is reciprocally mounted 10 the rod 30 carrying a cross-pin or key 31 which acts as a clutch member for engaging or disengaging the sleeve 26 to or from rotative action with the shaft 25, the key 31 extending diametrically through the shaft 15 25 in the slot 32 therein.

The end 33, of the sleeve 26, which extends inwardly past the gear 27, has formed therein a diametrically disposed slot, which, when registering with the slot 32, may be 20 engaged by the key 31 when the rod 30 is drawn outwardly for such engagement and by which action the sleeve 26 with its accompanying parts becomes non-rotatably attached to the shaft 25.

25 In suitable bearings 34 and 35 is mounted the vertically disposed shaft 36 which carries the flat spiral spring 37, the inner end of which is securely fixed to the shaft 36 as is customary in such devices and the outer end 38 is pivotally attached as at 39 to the short end of the L-shaped lever 40 which is pivotally mounted at 41 in the cross-beam 4.

30 A spring 37 is shown somewhat reduced in size for convenience of illustration, but in practice it will, when expanded, comparatively fill the space surrounding same within the truck.

35 Upon the lower end of the shaft 36 is mounted the large beveled gear 42 which meshes with the smaller gear 27 on the sleeve 26, which, when the spring is being wound up, is driven by the gear 27, but when the spring is imparting motion to the truck, the gear 27 will be driven by the gear 42.

40 45 A pan or plate 43 is installed intermediate of the gear 42 and spring 37 to suitably house the latter. For reciprocating the rod 30, I have shown pivotally attached thereto in any desired manner at 44 the long arm of the bell-crank lever 45 which is pivotally mounted at 46 upon a suitable support or arm 47, the short arm of the bell-crank 45 being pivotally connected as at 48 to the link 49, pivotally connected at 50 to the L-shaped 50 55 extension 51 of the lever 52 which is pivoted at 53 on the under side of the cross-beam 5 and extends centrally to a convenient position intermediate of the handles 7 and 8 as at 54. Thus when the end 54 of the lever is 60 moved either one way or the other the shaft 30 will be correspondingly reciprocated resulting in the locking or unlocking engagement of the sleeve 26 with the shaft 25.

65 On the extreme end of the shaft 30 and just outside of the pivotal connection 44 of

the bell-crank 45 therewith is pivotally attached as at 55 a short link 56 which at its opposite end is pivotally attached as at 57 to the like, but somewhat larger link 58, the opposite end of which is pivotally mounted as at 59 to the journal bearing 60 of the sleeve 26. The link 58 is so positioned in relation to the ratchet wheel 28 as to act as a pawl for co-operative engagement therewith when the shaft 30 is thrust inwardly 70 to its limit which is the reverse position to that shown in Figs. 1 and 2 of the drawings, such position causing the pivotal point 57 of said link to be drawn inwardly toward the shaft by the shortening of the distance 75 between the pivotal points 55 and 59, and, when the shaft 30 is fully extended, the distance between the points 55 and 59 will be lengthened, thus releasing the link 58 from its pawl-like engagement with the ratchet 80 wheel 28. A floating L-shaped lever 61 is pivoted at 62 to any convenient stationary portion of the truck chassis, the lower end of which rests against the outer edge of the link 58 and is actuated thereby, while the 85 upper end of the lever 61 impinges against the elongated flat pawl 63 pivotally attached to the chassis at 64 and engageable with the ratchet wheel 28 as at 65, said pawl being held normally down by a suitable spring 66, or by gravity as desired, it having a slot 67 in its free end through which extends the pin 68, acting as a guide for said free end of the pawl. The upward or disengaging movement of the pawl from the ratchet 90 wheel 28, as is evident, is accomplished by the upward movement of the short arm of the L-shaped lever 61, and which, occurs only when the pawl link 58 is swung outwardly 95 from said ratchet wheel.

100 From the foregoing it is apparent that there are provided two means for engagement with the ratchet wheel 28 to insure its being positively held stationary when the spring 37 is wound up and the lever 52 is so 105 connected as to hold the sleeve 26, with its accompanying parts, in non-rotatable engagement with the shaft 25, when in the position shown in Figs. 1 and 2 of the drawings. At this time if the lever 20 is adjusted 110 to the position shown in Fig. 1, the gear 12 on the shaft 9 will engage the gear 24 on the shaft 25, and, if the truck is being operated backwardly as for example down grade and loaded, the spring 37 will be 115 wound up, the ratchet wheel 28 being rotated in a backward direction unaffected by its co-operative pawls. As the truck advances and the winding of the spring proceeds the centermost turns of the spring will be tightened 120 first, that is to say, the maximum strain on the wound spring will come upon the point of contact 39 thereof with the lever 40 only after the spring is fully wound, and when that point of stress is reached, the 125 130

lever 40 will be actuated with sufficient force to counteract the pulling strain of the contractile helical spring 69 which normally holds the lever 52 in engaged position in respect to the shaft 25 and the gears 27. The connection of the lever 40 to the end of the lever 52, as indicated at 70, is such as to permit of the change of longitudinal relation of the two levers. When the lever 52 is thus automatically operated by the maximum tightening of the spring, the inward thrust of the shaft 30, in consequence thereof, through its connection with the end of the lever as before described, will release the sleeve 26 from non-rotatable engagement on the shaft 25 and simultaneously bring the pawls 58 and 63 into holding engagement with the ratchet wheel 28 and thus retain the spring 37 in its wound up position ready for subsequent employment at the will of the operator. This will, as is evident, release the truck axle 9 from positive engagement with any part of the mechanism except that either one of the gears 11 and 12 may remain in mesh relation with the gear 24 and idly operate the shaft 25.

Now, if it so happens that it is desirable to operate the truck in a forward direction with its load after the spring 37 has been thus wound up, it is evident that if the gear 12 is left in engagement with the gear 24 and the lever 52 is manually thrown back to its original position freeing the pawls from the ratchet wheel 28 and fixing the gear 27 with the shaft 25, the unwinding tendency of the spring will impart motion and power to the truck to the limit of the action of the spring. On the contrary, if it is desired to utilize the power of the winding spring in driving the truck backwardly, the lever 20 is so adjusted as to bring the gear 11 into meshed engagement with the gear 24, when the lever 52 may be adjusted to apply spring action to the axle 9 in a backward direction. Or if the truck may chance to be operated forwardly loaded and down grade, the spring may be wound as before described with the gears 11 and 24 in mesh and again its stored energy used as desired in subsequently propelling the truck in either direction.

Adjacent the free end of the lever 52 and against the outer face of the cross-beam 6 is pivotally mounted as at 71 a lever controlling member 72, it being a flat metal bar having notches 73 and 74 cut in the under edge thereof and in which notches the lever 52 may be engaged alternately.

On the inside of the handle 7 is pivotally mounted at 76 a thumb lever 77 in convenient proximity to one hand of a person operating the truck and by which the free end of the lever 72 may be lowered at any time for positive engagement with the lever 54, there being a link 78, pivoted at 79, con-

nected at 80, to the lever 77, and engaging the free end of the lever 72 for raising and lowering same. A flat leaf spring is shown at 75 for holding the pivotally united ends of the lever 77 and link 78 depressed which normally holds the free end of the member 72 upwardly and from engagement with the lever 52, thus allowing the latter freedom to act in either direction, it being normally held adjacent the notch 74 by the action of the spring 69 as before described.

By this means it is seen that the manually operative end 54 of the lever 52 may be held in either notch 73 or 74 of the member 72 for operating the truck in either direction by spring power or for winding up the spring when the truck is going in either direction, and as before stated, the spring 37 cannot become overwound due to the fact that the action of the lever 40 on the innermost end of the lever 52 will counteract the holding office of the spring 69 and thus throw the winding mechanism out of gear and at the same time hold the tension of the spring 37 by locking against rotation the ratchet wheel 28 on the sleeve 26.

While I have thus described one practical embodiment of my invention, it is to be understood that various modifications within the scope of the appended claims may be resorted to without departing from the spirit of the invention.

Having thus described my invention, what I claim and desire to secure by Letters Patent is:

1. The combination with a two-wheeled, single axle hand truck having a pair of handles for operating same, of a spiral spring carried by the truck adjacent the axle thereof, means intermediate of the spring and the axle whereby the spring may be wound up by the motion of the truck in either direction and subsequently the latter be operated by the spring when desired, and means intermediate of the handles of the truck whereby to control the operation of the spring.

2. The combination with a two-wheeled hand truck of the class described having a single axle and both wheels rigidly fixed to the axle, of a sleeve reciprocally mounted upon said axle and carrying two opposed beveled gears, a shaft carried by the truck centrally thereof and at right angles to the axle, beveled gears adjacent each end of said shaft, one for engagement with either of the beveled gears on the sleeve and the other for transmitting power from said shaft, a second shaft disposed at right angles to the first mentioned shaft and intermediate of its outer end and the axle, a beveled gear on said shaft meshing with the power transmitting gear of the first mentioned shaft, a spiral spring on said second mentioned shaft for storing energy imparted

thereto, means for shifting the sleeve on the axle for engaging the first mentioned shaft with either of the gears upon the sleeve or neither of them, and means for controlling the action of the spring either in transmitting power or reserving power substantially as described.

In testimony whereof I hereunto affix my signature in the presence of two witnesses.

JOHN JEWELL.
